Frederick S. Dunneau. ATTORNEY

UNITED STATES PATENT OFFICE.

GORMAN C. BURD, OF NEWARK, NEW JERSEY, ASSIGNOR TO AMERICAN CABLE COMPANY, A CORPORATION OF NEW YORK.

CABLE HITCH.

Application filed May 5, 1927. Serial No. 189,062.

This invention relates to a cable hitch and more particularly to a type of hitch or grip adapted for use in forming a sling for hoisting building materials, such as beams. 5 Among other uses it may be used as a tow-line or for the ends of a guy wire and the like.

The principal object is to provide a hitch which may be used to quickly form a non-10 slipping loop.

A further object is to provide a device which will be strong in structure and capable of sustaining a considerable strain.

A clear conception of the construction, operation and further objects of the invention may be had from the following specification in conjunction with the accompanying drawings in which

Fig. 1 discloses the invention in plan view, in use as a guy wire;

Fig. 2 is a side elevation of Fig. 1.

The now preferred form of invention comprises a steel bar 1 with lugs 2, 3 and 4 formed thereon. The bar 1 is shaped as 25 shown, having its end portion 5 bent away from the plane of the body of the bar. In the end 5 is secured by any well known means the end of a cable 6 in such a manner that the metal of the bar is forced into the 30 interstices of the strands of the cable, thereby making the cable an integral part of the bar 1.

The lugs 2, 3 and 4 on the body portion of bar 1 are positioned as shown in a staggered relation and their faces are notched to prevent the cable 6 from slipping out of contact therewith. These notches are cut in one side of the two outer lugs while the notch in the center lug is cut on the opposite 40 side.

In operation the cable 6 is passed around the object to be lifted or to which the cable is to be attached, such as pole 7, and the

body of the cable is caught between lugs 3 and 4. The bar 1 is then swung until the 45 lug 2 engages the cable. The cable 6 is now held in a tortuous path which provides sufficient friction to prevent the hitch from slipping so long as the strain on the cable 50 is uniform.

It will be apparent from the above that this form of hitch provides a strong and simple method of forming loops in cable which will be capable of sustaining considerable strain due to the strong integral fastening between the steel of the bar and the 55 cable and to the action of the lugs.

I claim:

1. In a hitch of the type described a bar having a plurality of lugs formed thereon in staggered relation, said bar having its end portion bent away from the plane of the bar, but lying in a plane parallel to said lugs, a cable secured in said end portion in such a manner as to be integral therewith, 60 said lugs holding the free end of said cable in non-slipping engagement when a strain 65 is placed on a loop formed thereby.

2. In a hitch of the type described a bar having a plurality of lugs formed thereon in staggered relation, said lugs having notches cut therein, said notches in the outer lugs facing in one direction, said notches in the center lug facing in the opposite direction, said bar having an end portion bent 70 away from the horizontal plane of said bar, a cable secured in said end portion in such a manner that the metal of said bar is forced into the interstices of the strands of 75 said cable thereby forming an integral joint, 80 said lugs holding the free end of said cable to form a non-slipping loop when strain is placed thereon.

In testimony whereof, I have signed this specification.

GORMAN C. BURD.

CERTIFICATE OF CORRECTION.

Patent No. 1,660,829.

Granted February 28, 1928, to

GORMAN C. BURD.

It is hereby certified that the name of the assignee in the above numbered patent was erroneously described and specified as "American Cable Company, a corporation of New York", whereas said name should have been described and specified as American Cable Co., a corporation of Delaware, as shown by the records of assignments in this office; and that the said Letters Patent should be read with this correction therein that the same may conform to the record of the case in the Patent Office.

Signed and sealed this 17th day of May, A. D. 1932.

(Seal)

M. J. Moore,
Acting Commissioner of Patents.
